MATCH PACKET

Rodney Southwick Pullen, Akron, Ohio, assignor
to Pullenlite Company, Philadelphia, Pa., a
corporation of Pennsylvania

Application August 23, 1932. Serial No. 630,144

15 Claims. (Cl. 266—29)

My invention relates to match packets in which the matches light during withdrawal.

One purpose of my invention is to reduce the thickness of a match packet at the head ends of the packet.

A further purpose is to provide a slot for match head withdrawal at the match head end of the packet having approximately full slot size sufficient to accommodate the head of the match across the packet from front to back and to reduce the slot dimension in the direction from edge to edge of the packet.

A further purpose is to form retardation to withdrawal of the match head end of a match through an opening provided for it by side flaps corresponding to position between the sticks of adjacent matches, freeing from retardation in a direction of the opening across from front to back of the packet.

A further purpose is to provide a packet having retardation to match head withdrawal exaggerated in a direction between the match heads and relieved in a direction at right angles thereto and to close the edges of the match packet.

A further purpose is to countersink the staple in a pull-and-light packet.

A further purpose is to taper the end of a wrapper for easy insertion into a bale.

Further purposes will appear in the specification and in the claims.

I have preferred to illustrate my invention by one main form only with slight variation, selecting a form which is practical, effective and inexpensive, but which has been selected primarily because it well illustrates the principles of my invention.

Figures 1 and 2 are perspective views of my packet, of which a portion is broken away in Figure 2 in order to show part of the interior construction.

Figure 1a is a perspective view of a form corresponding generally to Figures 1 and 2, but in which a staple passes through the packet.

Figures 3 and 4 are top plan views of two slightly different forms of wrap which may be used in forming the packet of Figures 1, 1a and 2.

Figure 5 is an edge elevation showing the construction of Figures 3 or 4 in partly assembled position with the matches in place and with a bale attached, but not yet folded.

Figures 6 and 7 are left elevations of Figure 5 with the bale partly folded and completely folded respectively, as distinguished from the flat condition of the bale in Figure 5.

Figure 8 is an edge elevation of the partly completed packet when the wrap has been folded from the position of Figure 6.

Figure 9 is an edge elevation of the packet after the wrap has been completed from the position seen in Figure 7.

Figures 10 and 11 respectively are transverse longitudinal sections taken between the matches showing the packet with the wrap of Figure 3 in Figure 10 and the wrap of Figure 4 in Figure 11. The thickness of the packet walls is exaggerated for the sake of clearness.

Figure 12 is a top plan view of a bale which may be used in the packets of Figure 1 and Figure 1a.

Figure 13 is an edge elevation of Figure 12.

Figures 14 and 15 are fragmentary enlargements of portions of Figures 3 and 4 respectively.

Figure 16 is a top plan view of a somewhat different form of wrap.

Figure 17 is an edge elevation of a completed packet using the wrap of Figure 16.

Figure 18 is a top plan view showing a modification and illustrating the wrap about to be inserted in the bale.

Figure 19 is a section on the line 19—19 of Figure 18.

In the drawings similar numerals indicate like parts.

In the packet shown in my Patent No. 1,694, 85
864 the matches 9 within the packet pass through two sets of openings or holes in line, those nearest the heads of the matches being peticcoated to allow the sticks of the matches to enter for normal holding of the matches and to provide retardation for match withdrawal by the peticcoating sides formed by star cuts within the material spread out from the cover during the insertion of the matches. This proved quite satisfactory in the character and extent of retardation provided and in the protection of the head compartment of the packet against flashes of flame from the ignited matches.

Because the material spread from the holes was equally spread in all directions some of it was spread in directions so as to bring the peticcoated material between the match sticks and the flat inner front and back walls of the packet, increasing the thickness of the packet at this point. As the packet was relatively thinner near the 100 stick end terminals of the matches and was tapered therefore from this point toward the heads, the thickness of the packet was still further increased by continuing the slope of this taper to the full end of the packet where the wrapper 110

is turned across the head ends of the matches at the outside. This offers a further objection in enlarging the match head compartment unnecessarily in a direction from front to back of the 5 packet, giving additional room for distribution of a flash of flame from an igniting match head, making a flash from the head compartment of the match both more likely and more serious than otherwise would be the case, due in part 10 to the additional air provided to support combustion of the match heads.

My invention has primarily to do with correction of this difficulty, rendered particularly desirable as regards the thickness by the necessary 15 thickening of the packet to provide closure walls at the side of the packet.

Describing first the form shown in Figures 3 to 10:—

The wrapper in Figures 3 and 4 is shown as 20 comprising inner front flaps 20, head end supporting walls 21 and 21', inner rear flaps 22, stick end match supporting walls 23, outer front flaps 24, outer head protecting end walls 25, outer rear flaps 26 and rear flap end extensions 25. These are divided from each other by score 25 lines permitting easy bending of the sheet as well as complete bending which may permissibly be provided by either single or double score lines at each place. Double score lines are 30 shown. The score lines dividing the several parts described appear at 28, 29, 30, 31, 32, 33 and 34.

In order to give side retardation of the match 35 heads on withdrawal, that is, retardation in a direction toward edges 35 and 36 respectively of the packet, rather than retardation due to engagement with the material surrounding the holes in a direction lengthwise of the wrap, that is, toward the score lines 28 and 29, the 40 holes 37 and 37' are elongated and this is preferably done by punching two holes 38 and 39, 38' and 39' at each hole position, which holes initially may be cut into each other and give a part of the benefit of my invention, but preferably do 45 not quite touch each other, leaving an intermediate portion 40, 40' which must be broken by the match as it is inserted, stick end first. This results in a larger portion of retarding material crowding against the sides of the match from the 50 direction of the two edges 35 and 36 of the wrap than would be the case if the holes cut into each other so as to remove part of this intervening material.

As the matches are inserted stick ends first 55 within these holes, and within the holes 41 provided to support the sticks of the matches near their stick ends, the matches first break this material at 40 or 40', if it has been left attached, and then pass on through, occupying part of the 60 space each of the two openings 38 and 39, or 38' and 39', and laterally swelling out the material of the wrap, ordinarily pulp board or some similar cheap flat non-metallic material, between them and the other matches or beyond these 65 matches in directions toward the edges 35 and 36.

The packets are further provided with match igniting material 42, and in Figure 3, at least, with printings 43 of glue for holding the flaps of the match packet together in their final position.

In Figures 1a, 4 and 11 the wrap is grooved longitudinally at 44 by pressing the cover material so as to be convex to the observer in these two positions and to present the concavities of 75 the grooves within the outside of the front and

the outside of the back of the packet, respectively, to receive the bar 45 and the bent ends 46 of staples 47.

Notwithstanding that the elongation of the 80 openings in the head end match-supporting strips 21, 21' fit in well with their showing in packets which need thinning because of the intended provision of edge closing bales (which tend to thicken the packet) these openings fit in well also with packets of the type shown in my Patent No. 1,694,864 in that they permit a packet to be 85 made having less thickness than in my original showing. The wrap and the edge view of the finished packet applying the invention to the form of my packet above are shown in Figures 90 16 and 17. In this form the type of elongation seen in Figure 15 is used.

The bale of Figures 12 and 13 comprises a central body portion 48, edge closing strips 49 and 50 and flaps 51 and 52. The division lines between these several parts comprise score lines which may be single or double, and are here 95 shown as double, appearing at 53, 54, 55 and 56.

Upon the middle section of the bale are printings 57 of glue intended to apply the bale to the 100 wrap. The bale is adapted to be fastened together in closed position by staples 47 which fit through grooves 58, 59 and 60 similar to grooves 45, which present their concavities away from the observer in Figure 12 to receive the bar 105 and bent ends of a staple for each packet.

In assemblage the wrap of Figure 3, or of Figure 4, is folded upon score line 29 and 30 to bring the walls 21 or 21' and 23 into opposite position parallel to each other for insertion of 110 the matches to the position seen in Figure 5, after which, or it may be before, the flap 20 is folded at right angles to the wall 21 or 21'.

At any convenient time prior to, or in the condition of the wrap seen in Figure 5, the bale 115 is applied transversely of the wrap, that is a quarter turn with respect to the view in Figure 12 and so that the intermediate portion 48 lies across and is glued to the back of flap 22 of Figure 3, or Figure 4, so as to lie as seen in Figure 120 5.

With the parts in the partly assembled position of Figures 6 and 7, the edge closure walls 49 and 50 are folded up along lines 54, 55 so that these edge closure walls and the flaps 51, 52 lie 125 in the position seen in Figure 6. By further bending upon lines 53 and 56 the flaps 51 and 52 are brought down to the position seen in Figure 7, it making no difference which of the flaps lies on top of the other.

In the position of Figure 7 the staple may be 130 inserted either from the top or from the bottom so that either its bar or its bent ends lie within the groove 58 and its bent ends or its bar lie within the contour of the two grooves 59 and 60.

From the position seen in Figure 7 the wrap is 135 bent along lines 31 to bring the flap 24 into engagement with the front wall of the packet as so far assembled, after which the wrap is folded about lines 32 and 33 to place the end section 25 across the heads of the matches and to bring the flap 26 into position so that the prints of glue 140 upon this flap will secure it to the rear wall of the back of the packet so as to finish the packet in the form of Figure 10.

If the insert has not been used, or if the insert as used has not carried the depressions for staple fastening and the wrap is so provided, staples may be put in the completed packet from front to back, or from back to front, as in Figure 145 150

ures 1a and 11. The staple in this use may be supplemental to or instead of the glue printings on the wrap; and the glue printings on the bale are intended rather to hold the packet conveniently in an intermediate condition than to hold the parts together in the final packet.

Whether the packet be complete at the time of stapling, or this be an intermediate step only, it is preferred to sink the bar and bent ends of the staple into the grooves preformed in the material so that the presence of the staples shall as little as possible distort the packet, and shall, in particular, avoid permitting the staple bar or ends to form a projection unpleasantly interfering with flat engagement of the walls which are intended to be fastened together. The form stapling together one flap only of the cover along with the bale is shown in Figure 10 and the other form, stapling together the completed packet is seen in Figure 11.

It will be evident that my packet is not swelled in a direction between the front faces by any material bent back to allow the matches to go through, but that all of the retardation provided will be concentrated in the portions 62, 62' lying between the matches whose distortion from the plane of the match receiving support 21, 21' will yield and lie within the spaces between adjoining matches.

With the retardation, given the matches will not move readily but will hold their positions until a considerable pull is exerted upon their stick ends, after which when started they will pass at high speed from their initial positions until they pass the ignition material. The openings 41 are not intended to offer any considerable retardation and the matches pass through ignited for the benefit of the user.

In Figure 16 I illustrate a wrap of the type shown in my Patent No. 1,694,864, having portions 20, 21, 22, 23, 24, 25 and 26, and additional portions 63, 64 and 65. The portion 63 provides a fold over the stick-ends of the match, the portion 64 folds over the front of the packet, and the portion 65 extends into a slit 66 in the wrapper, to hold the wrapper closed.

As shown in Figure 17, the packet is held together by a metal bale 67. The openings 37, the walls of which hold the matches at their head ends, are similar to those shown in Figure 14, but may equally well be of the type indicated in Figure 15, for example.

When using the paper form of bale, as illustrated in Figures 12 and 13, I find it very desirable to taper the effective end of the wrap for easy insertion into the bale. In Figures 3 and 4 I show the wrapper cut out at 68, so that, when the portion 21 or 21' of the wrapper is folded up with respect to the portion 22, and the portion 20 of the wrapper is preferably folded into a position parallel to the portion 22, as shown in Figure 18, the end of the wrapper will be somewhat tapered to assist in the insertion between the folded sides of the bale.

The tapering assists greatly in assembling the packet, since the wrapper as shown in Figure 18 may be inserted into the bale without the same degree of care as would otherwise be required.

It will be evident that as compared with my original Patent No. 1,694,864, the absence of the petticoating at the sides of the holes near the match head, i. e., in the direction of the thickness of the packet greatly reduces the friction, and particularly reduces such friction as would be applied by the pressure of the thumb and

finger on opposite sides of the packet. What would otherwise be a shoulder on account of the petticoating becomes instead merely a sloping side packet wall within which the head slides as a wedge. This is rendered more effective, of course, by the fact that the head end of the packet 25 forms a firm transverse support at this point and the scoring between the head end and the adjacent flaps gives abrupt bending at these points keeping the pressure initially from the heads of the matches.

As the matches are withdrawn the initial retardation is substantially all of it from the effective petticoating or fullness of material between the matches, rather than from a vice-like grip of the petticoating or of the hand of the user. As the head of the match passes through the opening toward the stick end of the packet it of course engages the walls of the side of the packet with whatever pressure the hand of the user brings upon them but it meets these surfaces as tangent surfaces and not as shoulders or filling between the sides as would be true in the case of petticoating.

It will be evident further that confining the retardant grip of the transverse packet wall upon the head to a grip upon the two opposite sides instead of all around the head reduces the danger of breaking the head loose from the stick of the match; and reduces the harm done in case of partial breakage of the head. At the same time the danger of injury from ignition of the matches within the head end compartment is reduced by the considerable reduction in the volume of air contained in the smaller head end compartment possible by reason of the absence of the petticoating at the side walls of the packet.

It will be evident that the elongated type of hole which is used near the match heads leaves a larger remaining body of stiffening material to support the packet transversely of the walls of the packet for a given center to center spacing of the matches.

In view of my invention and disclosure variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention, what I claim as new and desire to secure by Letters Patent is:—

1. In a match packet, cover walls, means for holding the cover walls together to form a packet and transverse match-holding walls having openings for the match sticks near the heads of the matches and near the stick ends of the matches respectively, the holes near the heads of the matches being elongated transversely of the packet and adapted to offer retardation to withdrawal of the heads chiefly upon the sides of the matches toward and away from the next matches.

2. A match packet having match cover walls, means for holding them together to form a packet and match-holding transverse walls apertured to receive and hold the individual matches, the effective apertures comprising each a plurality of openings in line across the packet merged into one when the match is in place and utilizing the material of the transverse packet wall between the plurality of openings to give retardation to withdrawal of the match.

3. A match packet comprising an outer wrap, 150

- stick-supporting walls transverse to the matches and adapted to hold the matches, having apertures elongated in a direction across between the front and back of the wrap and a bale arranged transversely of the packet to cover the side edge packet openings, the wrapper walls containing match striking material and a head end closing wall.
4. A match packet comprising stick-supporting apertured walls transverse to the matches and adapted to hold the matches and wrapper walls containing match striking material and outer wrapping and head-end closing walls, the openings for the matches near the match heads being elongated and larger near the adjoining cover portions than at an intermediate part of the length of the openings.
5. A match packet comprising stick-supporting apertured walls transverse to the matches and adapted to hold the matches and a bale arranged transversely of the packet to cover the side edge packet openings and wrapper walls containing match striking material and outer wrapping and head closing walls, the openings for the matches near the match heads being elongated in a direction across from front to back of the packet.
6. A match packet comprising stick-supporting apertured walls transverse to the matches and adapted to hold the matches and wrapper walls containing match striking material and outer wrapping and head closing walls, the openings near the match heads being laterally extended across the packet and larger near the ends of the openings than at the middle of the openings and the retardation to match head withdrawal being largely due to wall material between the apertures.
7. A match packet for matches withdrawable lengthwise comprising stick-supporting apertured walls transverse to the matches and adapted to hold the matches and a bale arranged transversely of the packet to cover the side edge packet openings, wrapper walls containing outer wrapping and head end closing walls, the openings near the match heads being laterally extended across the packet, and striking material in the path of movement of the match heads.
8. A match packet of the type in which the matches ignite on withdrawal comprising stick-supporting apertured walls transverse to the matches and adapted to hold the matches and wrapper walls containing match striking material and outer wrapping and head closing walls, the openings nearer to the match head ends of the match sticks comprising a pair of openings in line and having the sides of the elongated openings between the sticks offering the principal retardation to the passage of the heads of the matches.
9. A match packet of the type in which the matches ignite on withdrawal comprising stick-supporting apertured walls transverse to the matches and adapted to hold the matches and a bale arranged transversely of the packet to cover the side edge packet openings, wrapper walls containing match striking material and outer wrapping and head end closing walls, the openings nearer to the match head ends of the match sticks comprising a pair of curved wall openings in line and having the sides of the elongated openings between the sticks offering retardation to the passage of the heads of the matches.
10. A match packet of the type in which the matches ignite on withdrawal comprising stick-supporting apertured walls transverse to the matches and adapted to hold the matches and a bale arranged transversely of the packet to cover the side edge packet openings, wrapper walls containing match striking material and outer wrapping and head end closing walls, the openings nearer to the match head ends of the match sticks comprising a pair of triangular openings in line their apices facing each other and having the sides of the elongated openings between the sticks offering retardation to the passage of the heads of the matches.
11. In a match packet, a wrapper, a plurality of matches in the wrapper in a row side by side with their heads all pointing in the same direction, and a bale covering the sides of the row of matches, the edges of the wrapper being tapered for easy insertion into the bale.
12. In a match packet, a plurality of matches in a row side by side with their heads all pointing in the same direction, a wrapper positioning the matches and covering the match heads and having a countersunk depression and a staple uniting the wrapper and seating in the depression so as to be flush with the outer surface of the wrapper.
13. A match packet of the type in which the matches ignite on withdrawal comprising flap side packet wall and a stick-supporting apertured wall near to the heads, the openings near the heads being longer in one direction and shorter in another direction than the diameter of the match heads and thus presenting retardation to passage of the heads on opposite sides of the match sticks and substantially free from retardation in quadrature with respect to these sides.
14. In a match packet, a pair of adjoining wrapper flaps having printings of match-striking material upon them and having their adjoining side walls tapered, a section between and hingedly connected to the two flaps having apertures for match support, a bale adapted to surround the flaps, an apertured wall giving match support connected with one of the flaps and outer wrap flaps connected with the wall.
15. In a match packet, continuous tapered flap material forming inner flap walls and apertured match-supporting walls between them, outer flap walls, and a match-supporting wall between the inner and outer flap walls, in combination with paper bale material covering the sides of the matches at the edges of the packet and about the edges of one of the inner walls and match-striking material upon one of the inner walls, the inner wall about whose edges the bale extends being narrow in width across the packet to provide space for the bale material.

RODNEY SOUTHWICK PULLEN.
